United States Patent Office

Des. 193,398
Patented Aug. 14, 1962

193,398

DOLL

Walter L. Strauss, Scarborough, N.Y., assignor to Frankonia Products Inc., New York, N.Y., a corporation of
New York

Filed July 20, 1961, Ser. No. 66,003

Term of patent 14 years

(Cl. D34—4)

Fig. 1.

FIG. 2.

FIG. 3.

FIG. 1 is a front perspective view of a doll, showing my new design;

FIG. 2 is a reduced side elevational view thereof; and FIG. 3 is a reduced front elevational view thereof.

I claim:

The ornamental design for a doll, substantially as shown.
